UNITED STATES PATENT OFFICE.

JOHANNES HASSEL-JENSEN, OF COPENHAGEN, DENMARK.

FIRE-BOX.

1,240,971.

Specification of Letters Patent. Patented Sept. 25, 1917.

Application filed May 31, 1916. Serial No. 100,920.

To all whom it may concern:

Be it known that I, JOHANNES HASSEL-JENSEN, engineer, a citizen of the Kingdom of Denmark, residing at Copenhagen, in the 5 Kingdom of Denmark, and whose post-office address is No. 24 Sommerstedgade, Copenhagen, Denmark, have invented certain new and useful Improvements in Fire-Boxes; and I do hereby declare the following to be 10 a full, clear, and exact description of the invention, such as will enable others skilled in the art to which it appertains to make and use the same, reference being had to the accompanying drawings, and to letters 15 or figures of reference marked thereon, which form a part of this specification.

This invention refers to secondary air supply in fire-places, especially in boiler fire-boxes, and its object is to get secondary 20 air of comparatively high temperature distributed in such a manner in the smoke behind the fire-bridge, or the like, that perfectly combusting flames are produced there. In order to accomplish this, the mouthpiece 25 through which the secondary air is supplied, and which is disposed behind the fire-bridge, or the like comprises a plurality of members which, not only have a large surface for the smoke to act upon, so that the air, on 30 passing over them, is thoroughly preheated, but also have such a shape and such outlet openings that the smoke passes among them in the form of many currents encircling one another, while also the directions of the 35 issuing air-jets everywhere cross one another, causing the smoke in the zone behind the openings to whirl together in intimate contact with the hot secondary air. As experiments have proved, this makes it possible 40 to maintain a lively and perfectly combusting flame in said zone, whereby a greatly increased economy in firing is obtained, and formation of soot is prevented.

The shape of the members in question will 45 be best understood if we liken them to flattened trumpets, each with a long and narrow mouth and is also corrugated in such a manner that the long and narrow outlet opening does not run in a straight line but 50 in a zigzag line, an undulating line, or the like.

The drawing illustrates one mode of construction, by way of example. Figure 1 is a longitudinal section (along the line A—A

in Fig. 2) through a furnace with a secondary air mouthpiece of the kind here set forth.

Fig. 2 shows the mouthpiece seen from behind.

Figs. 3 and 4 are sections through a 60 mouthpiece member along the line B—B in Fig. 1 and the line C—C in Fig. 2 respectively.

Each of the members *a* (*i. e.* four in all) runs from the center backward in an undulating shape, the result of which is that obliquely running intervening spaces *h* for the passage of the smoke occur between the members, first on the one side and then on the other, and also that the members themselves at their rear are given corresponding undulating outlet openings *p* for the secondary air. The lower edges *s* of the members *a* fit into openings formed in a frame *b*, while flanges *o*, formed on the members above their lower edges, rest on said frame. On the front part of the flanges *o* there are hook-lugs *n* which mesh into corresponding recesses in a flange on the frame *b*. The latter can be secured by means 65 of bolts to the plates *d* and *e* belonging to the fire-box construction. An oscillating damper *f*, which serves to regulate the supply of secondary air, can be turned from the outside by means of a traction-rod *l*, 70 whose handle *t* is furnished with notches, so that the damper can be adjusted in the desired position. *m* is the usual masonry bridge, *e* is the grate supporter, and *r* is the 75 grate.

The construction here shown can easily be installed in boilers, or the like, which are already in use. In other respects the details shown in the drawing and set forth in the specification are immaterial to the invention 80 and may be altered in many ways.

I claim:

1. A mouth-piece for secondary air supply in fire boxes, comprising a flattened trumpet-shaped member corrugated in cross 100 section forming air passages adapted to direct air issuing from the outlet end in paths crossing one another.

2. A mouthpiece for secondary air supply in fire boxes, comprising a plurality of flattened trumpet-shaped members corrugated in cross section forming air passages adapted to direct air issuing from the outlet end 105

of each in paths crossing one another and spaced apart forming sinuous smoke passages between them.

3. In a furnace, the combination with the fire box thereof, of means for supplying secondary air to the furnace, comprising a plurality of flattened trumpet-shaped members corrugated in cross section forming air passages adapted to direct air issuing from the outlet end of each in paths crossing one another and spaced apart to form sinuous smoke passages communicating with said fire-box, and means to supply air to said members.

15 4. In a furnace, means for supplying secondary air thereto consisting of a plurality

of flattened trumpet-shaped members corrugated in cross section and placed across the path of the smoke and products of combustion, said members forming between them 20 sinuous smoke passages, and means for supplying air to said members whereby alternating currents of air and smoke cross one another.

In testimony that I claim the foregoing 25 as my invention, I have signed my name in presence of two subscribing witnesses.

JOHANNES HASSEL-JENSEN.

Witnesses:

P. HOFMAN-BANG,
ERNEST BOUTARD.
